(57) **CLAIM**

The ornamental design for a thermometer with golden tip, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front elevational view of a thermometer with golden tip, showing my new design;

FIG. 2 is a rear view thereof;

FIG. 3 is a top plan view thereof, the bottom plan view being a mirror image;

FIG. 4 is a right side view thereof;

FIG. 5 is a left side view thereof;

FIG. 6 is a perspective view thereof from the front; and,

FIG. 7 is a perspective view thereof from the rear.

The design is characterized by the gold color of the tip of the thermometer.
